UNITED STATES PATENT OFFICE.

JOHN DECOWSKI, OF MCKEES ROCKS, PENNSYLVANIA, ASSIGNOR OF ONE-HALF TO
MIKOLAJ MOZDZIEN, OF MCKEES ROCKS, PENNSYLVANIA.

BALLOON EQUILIBRIUM DEVICE.

1,304,858.

Specification of Letters Patent. Patented May 27, 1919.

Application filed January 2, 1919. Serial No. 269,206.

To all whom it may concern:

Be it known that I, JOHN DECOWSKI, a citizen of Poland, residing at McKees Rocks, in the county of Allegheny and State of Pennsylvania, have invented certain new and useful Improvements in Balloon Equilibrium Devices, of which the following is a specification.

The primary object of the invention is the provision of a ready means for maintaining the basket of a balloon normally horizontal notwithstanding the swaying and tipping of the gas bag, the basket also being adjustable relatively of the bag.

A further object of the invention is to provide a passenger car suspending device for balloons whereby the car is maintained horizontal at the desired distance below the balloon.

With these general objects in view the invention consists of the combination and arrangement of parts hereinafter fully described in connection with the accompanying drawing and in which like reference characters designate corresponding parts throughout the several views.

In the drawings, Figure 1 is an elevational view of the invention partly shown in vertical section,

Fig. 2 is an enlarged vertical sectional view of a portion of the invention and

Fig. 3 is a transverse horizontal sectional view taken upon line III—III of Fig. 2.

Referring more in detail to the drawing, my invention is herein illustrated in connection with a balloon having a gas bag 10 and a basket or passenger car 11 suspended therebeneath. A socket member formed of two disks 12 and 13 and connected together by screws 14 is suspended from the bag 10 by means of cords 15 attached as at 16 to the upper disk 12.

A ball 17 is journaled within a socket 18 centrally provided in the disks 12 and 13, whereby a threaded shaft 19 depending from said ball 17 is normally maintained vertical. It will be understood that the car 11 has a bail 20 with a central threaded boss 21 threaded upon the shaft 19 for adjustment longitudinally of the shaft.

A perforation 22 is provided in the bottom of the car 11 through which the shaft 19 extends while a head 23 upon the lower end of the shaft 19 limits the downward movement

of the car 11 when turned upon the said shaft.

The ball 17 being free to turn in the socket 18 after the manner of a universal joint, suspends the car 11 pendulumwise so that the car will automatically maintain a horizontal position with the shaft 19 vertical regardless of the swinging and swaying of the bag 10 and the tipping of the socket disks 12 and 13.

A U-shaped latch 24 is slidably mounted upon the bail 20 having serrated ends 25 adapted for locking engagement with the screw-threads of the adjacent side of the shaft 19. A spring 26 normally maintains the latch 24 in locking engagement with the said shaft for maintaining the car 11 in its adjusted position upon said shaft 19. A releasing lever 26' is pivoted upon the bail 20 and extends through the slot 27 provided in the latch 24, whereby the latch may be retracted from engagement with the shaft 19 when desired to turn the boss 21 upon the shaft for obtaining a different adjustment of the passenger car. The complete operation of the invention will be fully understood from this detailed description thereof, the ball 17 being adapted for positioning within the socket 18 during the assembling of the device when the screws 14 are removed and the disks 12 and 13 are separated. By means of my invention persons may travel in the car 11 without any inconvenience from the usual swaying movement of the balloon.

What I claim as new is:—

1. A balloon comprising a gas bag, a socket member suspended therebeneath, a ball mounted for universal movement within said socket member, a threaded shaft depending from the ball, a passenger car adjustably locked upon said shaft.

2. A balloon comprising a gas bag, a socket member suspended therefrom, a ball freely positioned within the socket of said member, a threaded shaft depending from said ball, a passenger car provided with a bail threaded upon said shaft, limiting means for the movement of said car upon the shaft and adjusting locking means between said car and shaft.

3. A balloon having a bag, a two-part socket member suspended therebeneath, a ball journaled within the socket of said

member, a threaded shaft depending from said ball, a limiting head upon the lower end of the shaft, a bail threaded upon said shaft, for longitudinal movement relatively thereof and a car carried by the bail having a perforation in the bottom through which said shaft extends.

4. A balloon having a bag, a two-part socket member suspended therebeneath, a ball journaled within the socket of said member, a threaded shaft depending from said ball, a limiting head upon the lower end

of the shaft, a bail threaded upon said shaft for longitudinal movement relatively thereof, a car carried by the bail having a perforation in the bottom through which said shaft extends, a U-shaped locking latch carried by the bail having toothed ends adapted for frictionally engaging said shaft, a normal positioning spring for the said latch and a releasing lever for the latter pivoted to said bail. 15

In testimony whereof I affix my signature. 20
JOHN DECOWSKI.
